US00D993340S

(12) **United States Design Patent** (10) **Patent No.:** **US D993,340 S**
(45) **Date of Patent:** **** Jul. 25, 2023**

(54) **EXERCISE APPARATUS**

(71) Applicant: **Jaquish Biomedical Corporation**,
Nevada City, CA (US)

(72) Inventors: **John Paul Jaquish**, Nevada City, CA
(US); **Paul Edward Jaquish**, Nevada
City, CA (US); **Henry David Alkire**,
Nevada City, CA (US)

(73) Assignee: **Jaquish Biomedical Corporation**,
Nevada City, CA (US)

(**) Term: **15 Years**

(21) Appl. No.: **29/767,072**

(22) Filed: **Jan. 20, 2021**

(51) LOC (14) Cl. **21-02**

(57) **CLAIM**

The ornamental design for an exercise apparatus, as shown and described.

DESCRIPTION

FIG. 1 is a perspective view of our new design of an exercise apparatus;

FIG. 2 is another perspective view of the design of FIG. 1; FIG. 3 is a bottom view of the design of FIG. 1;

FIG. 4 is a top view of the design of FIG. 1;

FIG. 5 is a side view of the design of FIG. 1, wherein the opposite side of the exercise apparatus is a mirror image thereof; and,

FIG. 6 is another side view of the design of FIG. 1, wherein the opposite side of the exercise apparatus is a mirror image thereof.

1 Claim, 5 Drawing Sheets
